PERCY VENABLES VERNON, OF KERESLEY, NEAR COVENTRY, AND RALPH JACKSON, OF COVENTRY, ENGLAND, ASSIGNEES TO ALFRED HERBERT LIMITED, OF BUTTS, COVENTRY, ENGLAND, A BRITISH COMPANY.

COAL-PULVERIZING MACHINE.

Application filed April 12, 1926, Serial No. 101,249, and in Great Britain May 2, 1925.

This invention relates to coal and similar pulverizing machines, of the kind in which a passage broadly of Y-shape is employed in connection with the supply of coal to the machine, to enable metal or other parts liable to injure the mechanism to be separated before entry into the machine. The coal to be pulverized descends one branch of the Y and encounters an upward blast of air from the stem portion thereof, and this is adapted to drive the coal through the other branch of the Y into the machine, while allowing the metal or other parts to fall through the stem part of the passage by which the air enters. The efficiency of such a separating device largely depends upon obtaining the correct degree of tortuosity of the passages and also the correct air velocity through them, and the object of the present invention is to provide simple means by which these results can be quickly and easily obtained, and also to provide ready access to the adjusting means and to such parts of the passage as may become accidentally chocked in use. According to our invention, we provide a separator construction in which a passage is arranged for an air current moving in a substantially upward direction. Material is introduced into this air current through an opening in one wall of the passage. We provide means for varying the velocity of the air current moving past this opening, and this may be suitably accomplished by varying the area of the air passage both above and below the incoming stream of material. We also provide means for varying the tortuosity of the passage, by adjusting the position of the point around which the material flows on entering the air current, or by adjusting the effective length of the air passage beyond the material opening. By means of the different adjustments provided, the device may be easily adapted to various materials and diverse conditions of operation. In the accompanying drawings, which illustrate a preferred construction of the separator passages,

Figure 1 is a vertical section through the part of the machine in which the passages are provided, the plane of the section being parallel to the axis of the machine, and

Figure 2 is a cross section on the line II-II of Figure 1.

In one method of carrying out the invention, in which the Y-piece is constituted by an arrangement of partitions in a hollow column 2 of substantially rectangular shape located at one side of the pulverizing chamber 3, the feeding mechanism (not shown) is arranged at, and mounted upon, the upper part 4 of the column, the feed entering the latter through the aperture 5.

The Y-passages may be unsymmetrical, and to form them, a partition 6 starting from the upper part of the side of the column remote from the pulverizing chamber extends downwards from the edge of the aperture 5 at an inclination towards the middle of the column. Here it is continued by a part 7 slightly curved towards the side of the column from which the partition commenced, and thereafter at 8 is inclined steeply towards the lower end of the same side of the column.

The outlet to the pulverizing chamber is an aperture 9 in the inner wall 10 of the column, and from the upper and lower edges of this aperture extend other partitions in the column indicated respectively at 11 and 12, and these co-operate with the partitions 6, 7 and 8 to form the Y-passage. The partition 11 forms a downwardly inclined lip at the upper portion of the outlet 9, and extension 13 of the lower edge of the lip terminating at about the middle of the curved part 7 of the partition above mentioned. The lower edge of this extension 13 forms the corner constituted by the junction of the two branches of the Y, one of which receives the material from the supply device, as indicated by the arrows, whilst the other forms an upwardly inclined supply branch to the pulverizing chamber 3. The lower edge of the aperture 9 is for a short distance inclined substantially at right angles to the lower side of the lip 11, and thereafter it unites with the partition 12 previously referred to, but as will be seen, the lower part of this partition 12 eventually is continued vertically downwards at 14. Thus, as will be seen, the partition 12, 14 divides the lower part of the column into two parts, of which the right hand part 15 serves for the introduction of hot air to the pulverizing chamber through the aperture 16, while the left hand part 17

is that by which air enters the lower part of the Y-piece, as is indicated by the arrows, and meeting the downward flow of coal, carries small particles into the pulverizing chamber through the aperture 9, whilst heavier portions, iron or other foreign matter in the coal, continue their downward journey and make their exit from the column by way of the part 17.

10 From the foregoing, it will be seen that a tortuous path is provided for the coal into the machine, inasmuch as it first descends the supply branch 18 and then, by the current of air entering the part 17 at 15 the lower part of the stem 19, it is swept round the bend 20 of the Y through the outlet branch 21 and into the pulverizing chamber. The degree of tortuousness is dependent upon the relationship between the 20 lower edge of the lip 13 forming the bend or corner of the Y and the lower edge 22 of the aperture 9 connecting with the pulverizing chamber.

By one feature, therefore, of the present 25 invention, a slidable plate 23 is mounted upon the partition 12 forming the lower wall of the branch into the pulverizing chamber and it can be raised or lowered so that its edge 24 acts as the lower edge of 30 the aperture 9 and has its level correspondingly altered, whereby, as will be evident, the passage round the bend and into the chamber is made more or less tortuous. This plate may be provided with a lug 25 35 formed by flanging over a projecting portion along one of its edges, and an elongated slot 26 can be provided in this flange for a stud or bolt 27 which is provided to extend through it and permit of clamping 40 it at the desired extension.

By a further feature of the invention, the previously mentioned curved portion 7 of the wall of the Y-piece is formed on a plate 28 which is vertically slidable within 45 the column 2. The continuity of the partition 6 is thus interrupted, and to prevent leakage and allow relative sliding motion they are arranged to overlap at 29. Movement of this plate varies the distance of the 50 partition 8 from the opposite one 12 thus varying the cross section of the rising passage between them, and consequently the air velocity therein.

The lower edge of the lip 13 forming the 55 corner of the Y-piece is formed separately from the upper part 11 and is connected by a web 30 with this slidable plate 28 so that it can also be raised or lowered, thereby varying the space between it and the lower 60 wall of the branch. The upper and lower edges of the web 30 are rounded to give a stream-like effect by preventing sudden alteration in section. The plate 28 is provided with elongated vertical slots 31 65 through which pass securing bolts 32 so

that the plate may be raised or lowered as desired to make the desired adjustments.

There is an aperture 33 in the side of the column which is closable by a door 34 having a quick fastening device 35, and this 70 aperture exposes both the adjustable members 23 and 28 and also gives access to the interior of the Y-piece at the junction of the branches with the stem. It is thus possible quickly to make such adjustments as may 75 be necessary to suit the coal supplied to the machine, and should any obstruction occur at this part it can quickly be reached and the trouble remedied.

In a certain type of machine to which this 80 invention is applied, the mechanism of the pulverizer is carried by a shaft which extends horizontally through the column containing the Y-piece. A space 36, therefore, is provided in the column for the shaft, by 85 means of spaced partitions 37 uniting with one another above the shaft at 38, and, if desired, below it also. There may therefore be Y-piece passages on each side of the 90 space 36, as clearly shown in Figure 2, and the passages unite in the column at the upper and lower end. With this arrangement, a closable aperture 33 is provided to give access to each of the adjusting means 95 and interiors of the Y-piece. The shaft extends through apertures 39 in the walls 100 of the column.

From the foregoing it will be seen that 105 effective separation of the metal or the like from the coal to be pulverized can be ensured by adjustment not only of the form of the passages but also by the change in intensity of the air currents obtained at the point of separation, by altering the effective cross-sectional area of the upwardly directed 110 air passages.

What I claim as my invention and desire to secure by Letters Patent of the United States is:—

1. A separating device comprising walls 110 defining an air passage extending in a generally upward direction, one of said walls having therein an opening for material to be fed downwardly into the passage against the upcoming current of air, and means for 115 varying the cross-sectional area of said air passage both above and below said opening.

2. A separating device comprising walls defining an air passage extending in a generally upward direction, means forming an 120 opening for the introduction of material from above into an intermediate portion of said passage, and means for varying the relative position of the walls of said passage both above and below said opening.

3. A separating device comprising walls defining an air passage through which air may flow in a substantially upward direction, and means for adjusting one of said 125 walls relative to the opposite wall, said ad-

justable wall having an opening there-through for the introduction of material into said air passage.

4. A separating device comprising walls defining an air passage through which air may flow in a substantially upward direction, means forming an opening for introducing material into said air passage, and means for varying the tortuosity of the path 10 through which said material travels.

5. A separating device comprising walls defining an air passage extending in a substantially upward direction, means forming an opening for introducing material into 15 said passage, and means for varying the

effective length of the air passage above said opening.

6. A separating device comprising walls defining an air passage through which air may flow in a substantially upward direction, means forming an opening for the introduction of material into said passage, and means for varying the position of the upper edge of the wall opposite said opening. ²⁵

In testimony whereof we have signed our names to this specification.

PERCY VENABLES VERNON.
